UNITED STATES PATENT OFFICE.

HOWARD L. WADSWORTH, OF CLEVELAND, OHIO.

SAND-CUTTING MECHANISM.

Application filed August 9, 1923. Serial No. 656,493.

The present invention relates as indicated to sand-cutting apparatus and refers more particularly to an improved apparatus for cutting, mixing and aerating the mold sand used in foundries. One of the principal objects of the invention is to provide in a unitary structure an apparatus which may be conveniently mounted beneath the floor level of a foundry and which is adapted to receive sand from the molds and to cut and aerate such sand and to then convey the cut sand back to the place of molding or to convenient storage bins. The present apparatus is therefore removed from the actual molding room and does not take up valuable floor space and the dust which occurs from the cutting operation is restricted from the air of the foundry. To the accomplishment of the foregoing and related ends, said invention then consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is a longitudinal sectional view through one embodiment of my invention; Fig. 2 is a similar view showing another embodiment thereof; and Fig. 3 is a transverse sectional view as taken on line 3-3, in Fig. 1, the cutting cylinder and its frame being shown in elevation.

The present novel apparatus is particularly designed for use in connection with automatic sand handling and preparing systems and may be added to existing installations, or may be built in as part of new systems. My apparatus, taken as a whole, consists of a stationary sand cutting and distributing unit which may be mounted to meet individual conditions, there being shown in the accompanying drawing only two of the many possible installations of the present apparatus. A single unit may be so installed as to handle all of the sand for an entire foundry, in which case suitable means are provided for conveying the sand to and away from the cutting and mixing device. It has been found very desirable, due to the limited floor space in most foundries and on account of the objectionable dust resulting from the sand mixing operation, to mount such mixing apparatus

in an enclosed casing beneath the floor line. The cutting and mixing mechanism may be mounted in connection with a hopper or chute into which the sand to be treated is dumped, or may be arranged in connection with a storage hopper in which a great supply of used sand is kept.

Referring now to Fig. 1, the floor is indicated by numeral 10 in which is provided an opening 11 leading to a chute or hopper 12. A screen 13 may be placed across this opening to separate coarse objects from the sand as it is dumped or shoveled into the hopper. The hopper 12 and the sand cutting and conveying device, to be presently described, may be fixedly mounted in any desired manner, the same being herein shown as carried by a unitary framework 14 composed of angle irons and girders. Mounted at the bottom of the hopper is a rotating sand cutting and mixing cylinder 15, which extends transversely across the outlet mouth of said hopper. The cutting cylinder is preferably in the form of a skeleton-like cylinder 50, on which are carried spiral blades 16, the structure being fixed to and carried by a rotating shaft 17. Power may be transmitted to shaft 17 through a chain 18, reduction gear box 19, and motor 20, it being understood, however, that the same power for controlling the conveying elements may be utilized if desired to rotate the cutting cylinder. As seen from an inspection of such figure, the sand contained in the hopper 12 falls by gravity against one side of the cutting cylinder, which acts upon such sand to cut and mix it. The cutting action of the cylinder tends to kick or throw the cut sand away therefrom in a direction opposite from the hopper 12. An enclosed casing or compartment 21 is provided to confine the sand as it is thrown from the cutting cylinder and a second chute or hopper 22 may be provided beneath the compartment 21, into which the mixed sand may fall. From this hopper 22 the treated sand may be then conveyed back to the place of molding or to suitable storage bins as desired. I have shown in the present embodiment of my invention a bucket conveyor 23 for this purpose, the lower end of such conveyor being located adjacent the bottom of hopper 22 and the upper end thereof extending above the floor line of the foundry. There may be also provided in connection with the above described apparatus means for con-

veying the sand from the place of molding to the opening 11 in the floor, such means being herein indicated by an endless conveyor belt 25.

5 In Fig. 2, I have shown a slight modification of my apparatus, which comprises the use of an enlarged hopper 30 mounted beneath an opening 31 in the floor 32. This hopper 30 may be used as a storage bin for 10 the used sand and is provided with an enlarged outlet 36 at the lower end. A screen 37 is located across the opening 31 which serves for the purpose of removing the coarse objects from the sand, similar to the 15 screen 13. The cutting cylinder 15 in this case is mounted at one side of the hopper and an endless conveyor belt 38, mounted directly beneath said cylinder and the outlet 36 of hopper 30, is employed to carry the 20 sand from the hopper to the cutting cylinder which then operates in the manner described above. An enclosed casing or compartment 40 is provided adjacent the other side of the cutting cylinder, which is adapted to 25 confine the cut sand as it is thrown from the cylinder 15. The conveyor belt 38 is extended beyond the cutting cylinder under the compartment 40 and is adapted to receive the treated sand thereon, as indicated 30 in Fig. 2. From the compartment 40 the conveyor belt may lead to any suitable mechanism, such as a bucket conveyor or the like, for conveying the sand above the floor line to a distributing conveyor or to suitable 35 storage bins. The structural frame work of this last described embodiment of the invention is also intended to be unitary and may consist of angle irons 43 and longitudinal girders 44.

40 It will be seen from an understanding of the foregoing that I have accomplished the objects primarily stated and that I have provided a very simply constructed apparatus for use in cutting and treating sand, 45 which may be conveniently mounted beneath the flooring of a foundry. The present apparatus is very easy to operate and does not take up valuable floor space. It is also so constructed that it may be readily adapted 50 for a continuous sand cutting and conveying system.

55 Other modes of applying the principle of my invention may be employed instead of the one explained, change being made as regards the mechanism herein disclosed, provided the means stated by any of the follow-

ing claims or the equivalent of such stated means be employed.

I therefore particularly point out and distinctly claim as my invention:—

60 1. A sand cutting apparatus including in combination a hopper having convergent walls, a sand cutting cylinder mounted at the outlet of said hopper, a casing enclosing the discharge side of said cylinder, and means for conveying the cut sand from said casing.

65 2. A sand cutting apparatus including in combination a hopper, a sand cutting cylinder mounted adjacent the lower end of said hopper, means for conveying the sand from said hopper to said cylinder, a casing enclosing the discharge side of the cylinder, and means for conveying the cut sand from said casing.

70 3. The combination of a foundry floor having an opening therein, a screen covering said opening, a hopper mounted beneath said floor and said screen, a sand cutting cylinder mounted adjacent the lower end of said hopper, means for conveying the sand from the hopper to the cylinder, a casing enclosing the discharge side of said cylinder, and means for conveying the cut sand from said casing above the level of said floor.

75 4. A sand cutting apparatus including in combination a vertical hopper having an opening at its lower end, a sand cutting cylinder mounted across said opening, a casing enclosing the discharge side of said cylinder, 80 said casing being open at its lower end and having conveyor means mounted adjacent said casing opening.

85 5. A sand cutting apparatus including in combination two relatively arranged chambers having a connecting passage, one of said chambers being open at the top and the other at the bottom thereof for the reception and discharge of material, and a sand cutting cylinder mounted in said connecting 90 passage.

95 6. A sand cutting apparatus including in combination a sand cutting cylinder, means for supplying sand to said cylinder, and an enclosing casing mounted at the discharge 100 side of said cylinder, the wall of said casing opposite the cylinder extending below the line of discharge therefrom.

105 Signed by me, this 7th day of August, 1923.

HOWARD L. WADSWORTH.
